UNITED STATES PATENT OFFICE.

SAMUEL F. BUNKER, OF CHICAGO, ILLINOIS.

KEY FASTENER.

Application filed March 7, 1927. Serial No. 173,410.

The object of my invention is to provide a simple and effective device which may be conveniently carried in a pocket, and used in connection with door knobs and locks of various kinds to prevent the key of the door, when locked on the inside, from being turned or thrust out of the lock by another key or instrument inserted from the outside.

In particular, the object of my invention is to so form and arrange the key fastener that it may be very cheaply constructed and easily snapped into place by a simple movement, and when properly positioned within the loop of the key handle will prevent tampering with the key.

In the drawing:

Fig. 1 is a perspective view of my key fastener in connection with the door knob and key of the usual type;

Fig. 2 is a face view of the door plate and knob partially in section to better show the fastener in place, and illustrating in dotted lines the position assumed by the fastener before its insertion into the key; and

Figs. 3, 4 and 5 are modified forms of the fastener.

The fastener, as illustrated in Figs. 1 and 2, is applied to the shank A of a door knob B which extends outwardly from a door plate C in which is a key hole D. The key E extends outwardly from the key hole and presents its handle F in flatwise relation to the door knob, which is the position assumed by the key when in locked relation. In order to prevent the key from being withdrawn, it is necessary to prevent it from being turned into edgewise relation to the knob, and the fastener of the present invention is designed to prevent such turning.

The fastener is in the form of a spring loop G which comprises side members H which converge downwardly toward the reversely bent end I which is of U-shaped formation. The sides are outwardly bowed or bulged at oppositely disposed intermediate points J, and thence bent inwardly toward one another to afford contracted neck portions K, above which the terminal portions L of the side members are backwardly bent to give the open upper end of the fastener a flaring mouth portion, and the ends terminate in inwardly bent lips M. This gives to the entire fastener the exterior configuration of an arrow head tapering to a close point and open at its base with an interme-

diate neck or contraction where the body of the fastener merges into the base.

As shown in Figs. 1 and 2, the fastener is formed of a flat strip of metal bent to the intended configuration. In Fig. 3, the same configuration is secured by stamping the fastener from a flat sheet of metal to afford a flattened and closed tip end N from which the side members extend, being twisted at the points O to present themselves in edge-wise relation to the general plane of the fastener.

Fig. 4 shows a similarly configured fastener formed of round wire. Fig. 5 shows a fastener stamped from a sheet or plate of flat metal, but without the twisting at the points O which characterize the fastener of Fig. 3.

In using the fastener, the same will first be slipped onto the shank of a door knob by bringing the lips of the open mouth of the fastener into register with the sides of the shank, after which an endwise thrust will cause the terminal portions of the shank to spread and a continued thrust will force the fastener past the contracted neck portion until it assumes the position indicated in dotted lines in Fig. 2. In this position, the body portion of the fastener will embrace the door knob shank which lifts the fastener sufficiently, so that it may be swung down into alignment with the aperture in the door key, but with the tip end of the fastener elevated above the aperture to afford the necessary clearance.

With the fastener thus aligned, a downward pressure against the upper end of the fastener will force the fastener along the door knob shank past the contracted neck portion and until the door knob shank is embraced by the flaring terminal portions, as indicated in full lines in Fig. 2. With the parts in this position, the key will be held against turning, and, at the same time, the fastener will be held under spring pressure in position around the door knob shank, being held in place by the inwardly converging loop portions.

In order to remove the fastener from the door knob, it is first thrust upwardly a sufficient distance to clear the key, after which it may be withdrawn and will spread sufficiently to permit the neck and the lips to free themselves from the door knob.

The invention is one which may be positioned or removed by a simple thrust or

pull, as the case may be, and yet affords sufficient spring tension to firmly grip the door knob shank when in place and thus prevent accidental displacement. At the same time, the provision of the contracted neck in conjunction with the inturned lips firmly positions the key holder at a definite point on the door knob, so that a tight fit is insured and rattling or maladjustment prevented.

I claim:

1. A key fastener in the form of an open ended loop of spring material configured to afford a tapered closed tip end merging into side sections bowed outwardly in opposition to one another and inwardly to afford reduced neck portions, the side sections be-

yond the neck portions being backwardly flared away from one another to the degree required to embrace the shank of a door knob, substantially as described.

2. A key fastener in the form of an open ended loop of spring material configured to afford a tapered closed tip end merging into side sections bowed outwardly in opposition to one another and inwardly to afford reduced neck portions, the side sections beyond the neck portions being backwardly flared away from one another to the degree required to embrace the shank of a door knob, and the tip ends being inwardly bent to afford oppositely disposed lips, substantially as described.

SAMUEL F. BUNKER.
